WALL CONSTRUCTION.

Original application filed October 2, 1925, Serial No. 60,029. Divided and this application filed April 28,
1926. Serial No. 105,162.

This invention relates to a method for constructing and applying fibre, plaster, pulp and other types of boards having a paper or other fibrous surface, and especially types 5 suited for walls, ceilings, and building construction.

The invention embraces a new method for concealing joints, nails or other fasteners used in applying such boards, so that the wall 10 or other surface made therefrom shall have a continuous surface of the material which forms the surface of the board. The invention also includes the product.

The principal objects of my invention are 15 to provide a simple and efficient means of concealing joints, nails or other fasteners, in wall boards of the paper lined type, to eliminate the necessity of using any putty or filler which would form a non-homogeneous 20 surface, and to enable a wall or ceiling to be built of wall boards without the necessity of having any panelling or projecting strips or other covering, thus making the finished wall or ceiling look as smooth as a wall built 25 of lath and plaster.

This invention is applicable to fiber boards, as well as boards made of other materials, and especially relates to such boards when applied to building construction to replace lath and plaster.

Heretofore, when wall boards or other composition boards have been used in the construction of walls and ceilings, it has been found necessary to conceal the heads of nails, 35 and of joints between the boards, by means of strips or panelling. While putty has been used to fill such cracks and cover such fasteners, this method has been unsatisfactory, for the two different types of surfacing, that is, 40 the paper or other fibrous surfacing of the board, and the putty, are readily distinguishable when painted or calcimined, or even when finished with a wall paper. Many substitute methods have been devised but 45 none so far has proven entirely satisfactory. My new method eliminates the difficulties experienced with the methods used in the past and furnishes a continuous paper or fiber surface which effectively conceals nail heads 50 and other fasteners, and also the joints.

All of the figures are somewhat diagrammatic in character, and show cross sections through wall boards. Fig. 1 shows a

cleavage plane in the outer or finishing layer or liner of a wall board. Fig. 2 shows how 55 the liner may be cut to the cleavage plane and then folded back to permit the driving of nails. In Figs. 3 and 5, the liner is cut and folded in a somewhat different manner. In Fig. 4 a strip is cut from the liner and the cut-out so formed is covered with a substitute strip. Fig. 6 illustrates the joint between adjacent wall boards after the nails have been driven to secure the boards to studding, but before the cut-out has been 65 filled with the finishing material. Figs. 7, 8, 9 and 10 show different ways of filling the cut-out to cover the joint.

The invention is carried out by leaving cleavage planes in the board, preferably between certain layers of the paper or other material used for liners, and parallel to the face of the liner. I define "cleavage plane" for the purpose of this invention as a plane of separation between layers of paper or 75 other fibrous materials so that the layers may be readily separated at predetermined areas. Methods for forming such planes will be described hereinafter. The zones of cleavage are located in the board at the places where 80 the board is to be nailed or otherwise fastened to the structure, that is, these cleavage zones register with the studding or other framing to which the board is to be fastened.

Fig. 1 shows a portion of a cross-section of a board containing a cleavage plane made according to my invention. The central portion 1 may be of pulp fibre, or plaster, or any other filling common in wall board construction. The liners 2 and 3 may be of paper or other fibrous material suitable for surfacing boards, and may vary greatly in thickness. Both liners, or either one, may have a cleavage plane, 4, for the purpose of 95 this invention.

A cleavage plane may be made by gluing two sheets of covering material together in such a way that the glue is omitted at the cleavage zone. In another method I propose to insert a thin ribbon of paper between the layers of pulp as they are being laid down by a paper machine. For example, if the covering layer or liner is a fiber board made of four layers of pulp, pressed together, the thin ribbon of paper

may be inserted between the first and second, or the second and third layers, or between the third and fourth layers of the pulp. This thin ribbon will form a cleavage zone which causes the layers of pulp to be easily separated at the plane. Other methods may be used to form the cleavage zone.

The width of the cleavage zones can be 10 made as desired, but in general they will not need to be over 2", but may vary from $\frac{1}{2}$ " to 6". The location of the cleavage zones can also be varied, but in general, they should be along the edges of the boards and 15 spaced about 16" or 24" apart, or the standard spacing of studding. The cleavage zones can be indicated by markings on the surface of the liners as desired, such markings to be of such a character that they will 20 not destroy the continuity of the surface.

When the cleavage zone is distant from the edge of the board, as in Figs. 2, 3, 4 and 5, the surface of this plane is slit with a knife, or other convenient instrument, and 25 is turned back. Such a knife should be provided with guard wings so adjusted that it will cut into the paper liner, or other fiber surface, only a certain fixed depth, that is, to the cleavage plane.

30 Fig. 2 shows a cross-section of a board in which the finishing layer or liner has been slit to the cleavage plane and the resulting flap has been turned back, exposing the cleavage zone. This exposed cleavage plane should register with the studding or other framing to which the board is to be fastened. The board is then fastened by means of nails, or other fasteners, at the exposed cleavage zone, as shown in Fig. 2. The nail, or other fastener, is driven into the board far enough so that the top of it is flush with or lower than the exposed surface of the cleavage plane 4. Either the underside of the flap 5 which has been turned back, or the exposed cleavage plane 4, is coated with glue or some other suitable adhesive and the flap 5 is then replaced to its original position. The nails, or other fasteners, are thereby effectively concealed, 50 and a continuous surface of the finishing layer on the wall board forms the surface of the wall or ceiling, or other structure.

Fig. 3 illustrates a modification of the method shown in Fig. 2. For applying the board, the finishing layer is slit in the same manner, but the layer is peeled away from the cleavage planes on both sides of the slit instead of one side as in Fig. 2.

In Fig. 4, a double slit is made in the finishing layer or liner and the strip of finishing layer so detached is entirely removed, exposing the cleavage zone. After the board has been fastened, the strip so removed may be replaced, but, to secure a continuous surface, care must be taken to make

the strip which has been removed register exactly with its former position. If it is not desired to reuse the strip so removed, another concealing strip can be substituted. A strip of paper 6, or other fibrous material 70 of about the same character and thickness as the strip removed, but appreciably wider, is pasted or otherwise fastened, by a suitable adhesive, to the cleavage plane, after the board has been fastened to the studding or 75 other framing. As shown in Fig. 4, this strip 6 overlaps the slits on either side of the removed strip but is not pasted to the finishing layer or liner where the overlap occurs. A knife is then used to slit both 80 this strip and the finishing layer or liner to the cleavage plane at the points A and B in Fig. 4. The trimmings thus formed from the concealing strip and the liner are removed and the concealing strip is then fastened by glue or other suitable adhesive to the cleavage plane. In this manner a continuous surface is produced due to the perfect fit of the concealing strip in the depression of the liner. 85

Fig. 5 shows the board after it has been fastened to the studding or framing, with the nails concealed by the method illustrated in Fig. 3, with the joint of the two abutting papers directly above the head of the nail. 90

When it is desired to conceal a joint such as is caused by two boards butting against one another, as shown in Figs. 6, 7, 8 and 9, the procedure is essentially the same. The cleavage zone extends back from the edge of the board a given distance, as shown. The finishing layer may either extend beyond the edge of the board or may be cut back from the edge of the board. 100

Fig. 6 shows a cross-section of two boards 105 butting against each other with the finishing layer or surface of the liner cut back a certain distance from the joint and with the nails in place, the top of the heads being flush or slightly below the cleavage plane. 110 The boards may butt tightly against one another or may be left with a space between them as illustrated in Fig. 6. If a space is left between the boards, I prefer to fill this with a suitable putty or other filler so that 115 it will be flush with the cleavage planes.

Fig. 7 shows one method of carrying out my invention to conceal the joints. If the finishing layer or liner has been cut away so that the edge is a straight line, or approximately straight, a strip of paper, or other fibrous material, of the same thickness as the finishing layer, wide enough to cover the exposed cleavage zones of both boards is butted against the edge of one of the finishing layers, and is glued, or otherwise fastened by a suitable adhesive, to the exposed cleavage plane. The paper, or other fiber strip 6 overlaps but is not glued or fastened to the finishing layer which it overlaps. A 120 125 130

slitting knife is then run down at the point B, through both the covering strip and the finishing layer underneath, and to the cleavage plane, and the trimmed strips of finishing layer and covering strip are discarded.

The covering strip is then glued, or otherwise fastened, to the cleavage zone and forced down flush with the finishing layer.

10 The method of Fig. 7 may be varied as shown in Fig. 8, in which the covering strip 6 overlaps the finishing layer on both boards and is trimmed and finished in the manner described for Fig. 4.

15 Fig. 9 shows the finished construction with the nails, or other fasteners, in place, and the joint concealed with a covering strip corresponding in thickness and surface texture with the paper or other fiber used in the finishing layer of the board, thereby exposing a continuous homogeneous surface of similar material. The hairline joints at the points where the finishing layer and covering strip butt together may be disregarded.

20 They are practically invisible.

If the board has been constructed so that the finishing layer extends beyond the edge of the board, as shown in Fig. 10, the method used will be similar to that for Fig. 7, except that the finishing layer is continuous and the joint which appears at the left in Fig. 7 will not be present. The method of making the joint at the right will be the same as for Fig. 7.

35 While the illustrations show the use of nails in fastening the boards, other fasteners may be used. The cleavage plane may be placed in one liner or both liners, and may be placed close to the surface or at a considerable depth below the surface of the liner as appears desirable.

40 Wall boards expand and contract in varying amounts with changes in temperature and humidity and the joints may therefore be subject to considerable strain. Ordinary paper or other fibrous material, if used as a covering strip over the joints in walls or ceilings covered with boards which have a large expansion and contraction may not expand and contract sufficiently to prevent breaking of the joint. Under these conditions I have discovered that if the covering strip is creped slightly it contracts and expands sufficiently to prevent such cracking. The 45 creping can be made so slight that it cannot be readily distinguished from the smooth surface of the board, yet this is usually sufficient to compensate for the contraction and expansion of the board.

50 Throughout the specification the word "wall" has been used in its generic sense to include not only side walls but also ceilings and other like areas.

I claim:

1. A wall comprising studding, lined boards

nailed thereto with their edges adjacent one another, the lining on one side of said boards adjacent the edge being of decreased thickness to form a recess, and an inset of lining material arranged in said recess flush with 70 the wall surface and covering the joints and nails.

2. A wall comprising studding, lined boards nailed thereto with their edges adjacent one another, the liner of one at least 75 of said boards being cut away to form a recess and an insert secured in said recess arranged flush with the wall surface and covering the joints and nails.

3. A wall comprising studding, lined 80 boards nailed thereto with their edges adjacent one another, the lining on one side of said boards adjacent the edge being of decreased thickness to form a recess, and an inset of creped lining material arranged in 85 said recess flush with the wall surface and covering the joints and nails.

4. A wall comprising studding, lined boards fastened thereto with their edges adjacent one another, the lining of said boards 90 being reduced in thickness along its edge to a cleavage plane forming a recess, and a strip of lining material arranged in said recess flush with the wall surface and covering the joint and fastening means.

5. The method of concealing wall board fasteners and joints which comprises removing a strip of finishing layer from a cleavage plane in a board liner, fastening the board in place at the exposed cleavage plane, 100 and attaching covering material over the fasteners and joint to exactly fit the cut-out.

6. The method of concealing wall board fasteners and joints which comprises removing a strip of finishing layer from a cleavage plane in a board liner, the cut-out so made registering with the studding or other framing to which the board is to be fastened, fastening the board in place at the exposed cleavage plane, and attaching a 105 strip of covering material over the fasteners and joint to exactly fit the cut-out, said covering material having about the same composition and surface as the finishing layer that was removed.

7. The method of concealing wall board fasteners and joints which comprises removing a strip of finishing layer from a cleavage plane in the board liner, the cut-out so made registering with the studding or other framing to which the board is to be fastened, fastening the board in place at the exposed cleavage plane, attaching a strip of covering material of sufficient width over the fasteners and joint to overlap at least 115 one edge of the adjacent cut-out, said overlap not adhering to the finishing layer, cutting through the overlap and finishing layer to the cleavage plane, discarding the strips of trimmed finishing layer and covering 120

strip, and attaching the balance of the trimmed overlapping covering strip to the exposed cleavage plane.

8. The method of concealing wall board fasteners and joints which comprises removing a strip of finishing layer from a cleavage plane in the board liner, the cut-out so made registering with the studding or other framing to which the board is to be fastened, fastening the board in place at the exposed cleavage plane, attaching a strip of covering material of sufficient width over the fasteners and joints to overlap both trimmed edges of the cut-out, said overlapping covering strip not adhering to the finishing layer, cutting through the overlap and finishing layer to the cleavage plane at both edges, discarding the strips of trimmed finishing layer and covering strip, and attaching the balance of the trimmed covering strip to the exposed cleavage plane.
9. The method of concealing wall board fasteners and joints which comprises removing a strip of finishing layer from a cleavage plane in the board liner, the cut-out so made registering with the studding or other framing to which the board is to be fastened, fastening the board in place at the exposed cleavage plane, attaching a strip of covering material of sufficient width over the fasteners and joint to overlap both trimmed edges of the cut-out, said overlapping covering strip not adhering to the finishing layer, cutting through both edges of the overlapping covering strip and through the

finishing layer to the cleavage plane, discarding the strips of trimmed finishing layer and covering strip, attaching the balance of the trimmed covering strip to the exposed cleavage plane, said strip of covering material being of about the same thickness and about the same composition and surface appearance as the finishing layer on the surface of the board. 40

10. The method of concealing wallboard fasteners which comprises exposing a cleavage plane in the liner of the board, fastening the board in place at the exposed cleavage plane and covering the exposed portion to produce a substantially smooth surface. 45

11. The method of concealing wall board fasteners which comprises cutting out a strip of finishing layer from a cleavage plane in the liner, removing said strip, fastening the board in place at the exposed cleavage plane, 50 re-inserting the cut-out strip of finishing layer so that it registers with its former location, and there attaching it to the exposed cleavage plane.

12. The method of concealing wall board fasteners and joints which comprises removing a strip of finishing layer from a cleavage plane in the board liner, fastening the board in place at the exposed cleavage plane, and attaching a strip of covering material 55 over the fasteners and joint to exactly fit the cut-out from which the strip was removed.

In testimony whereof I affix my signature.
HOWARD F. WEISS.
